DES. 1970

Giles A. Kelley of St. Louis, Mo.

Letters Patent No. 19,970 Dated July 21, 1863.

Design for the Doors of a Stove.

The schedule referred to in these Letters Patent and making part of the same.

To all whom it may concern:

Be it known that I, Giles A. Kelley, of the City and County of St. Louis and State of Missouri, have invented or produced a new and original design for stove doors, and I hereby declare that the following is a full and faithful description thereof, reference being had to the accompanying drawings, and to the letters of reference marked thereon, and made to form a part of this specification.

The nature or subject matter of this invention relates to the peculiar configuration of the external surface of doors for stoves, as produced in cast metal, the same being made to represent panelled or batten work secured with bolts, as hereinafter described. In reference to the annexed drawings, Fig. 1 represents one of the doors used at the sides of the stove. Fig. 2 represents the fire door at the front of the stove, and Fig. 3 represents one of the sliding or bassing doors at the front of the stove, leading or opening into the ash pit, all of which will be formed at the same design and style, with reference to their external configuration, and will be produced in suitable cast metal.

A. A. A. represents the frames, and B. B. B. the panels or batten strips of the doors which will be cast with the projecting bolt or rivet heads a. a. a. and the spaces between the panels or batten strips, B., will be occupied with an imitation of wooden bead work, as seen at c. c. c., the whole being cast solid together.

2

DES. 1970

Moving thus described my invention, what claim as new
and desire to secure by Letters Patent is

The herein described design for stone doors comprising the
frames, panels or batten strips, R.C. and bolt or rivet heads, as represented
and specified.

In testimony of which invention I have hereunto set my
hand and seal this 26 day of May 1868 in the presence of witnesses.
